UNITED STATES PATENT OFFICE

JOHN S. JOHNSON, OF LULING, TEXAS

SPEAR

Application filed April 9, 1931. Serial No. 528,870.

This invention relates to new and useful improvements in a spear.

One object of the invention is to provide a spear of the character described, specially designed for use in pulling pipe stuck in a well bore.

Another object of the invention is to provide a tool of the character described that may be readily inserted into a pipe in the well bore and engaged therewith and through which the pipe may be pulled, or which may be readily released from the pipe and withdrawn in case the stuck pipe can not be dislodged and removed.

With the above and other objects in view, the invention relates to certain novel features of construction, operation and arrangement of parts, an example of which is given in this specification and illustrated in the accompanying drawing wherein:

Figure 1 shows a side elevation of the spear partly in section and shown in engagement with the pipe to be pulled.

Figure 2 shows a cross sectional view thereof taken on the line 2--2 of Figure 1.

Referring now more particularly to the drawing wherein like numerals of reference designate similar parts in each of the figures, the numeral 1 designates a mandrel which is downwardly flared and whose lower end has the tapering guide point 2. The numeral 3 designates a reduced shank preferably formed integrally with the mandrel and which has the external left hand threads.

Threaded onto said shank there is the coupling 4 to which the tubular operating string 5 is connected preferably by right hand threads. There are a plurality of downwardly tapering slips 6 whose surfaces have the

teeth 7 to engage with the pipe 8 to be pulled and the mandrel 1 has the external keys 9 which work between said slips. The upper ends of the slips are connected to a ring 10 which surrounds the lower end of the coupling 4 and whose upper end has the inwardly extending flange 11. Threaded onto the lower end of the coupling there is a ring nut 12, which is engageable with said flange to prevent the detachment of the slips from the

There is a coil spring 13 around the coupling which is seated on the flange 11 and whose upper end engages the annular flange 14 on said coupling.

Threaded into the upper end of the shank 3 there is a stop 15 for a purpose to be herein-after stated.

In use the spear is assembled as shown in Figure 1 and inserted into the pipe to be pulled, the guide 2 directing the spear into the pipe. The teeth 7 will be held by the spring 13 in frictional engagement with the inside wall of the pipe 8 and upon an upward pull through the operating string 5, the mandrel 1 will expand the slips 6 into secure engagement with the pipe 8. An upward pull may then be exerted on the string 5 and the pipe 8 thus dislodged and pulled. If the pipe 8 can not be pulled the operating string 5 and collar 4 may be turned to the right, the keys 9 holding the mandrel against turning. As the coupling 4 is turned on the threads 3, it will move upwardly and the ring nut 12 will engage the flange 11 and a continued rotation will cause the mandrel 1 to move downwardly relative to the slips 6, permitting said slips to contract and release the pipe and the spear may then be pulled out, leaving the pipe in the bore. The stop 15 will prevent the complete detachment of the coupling 4 from the shank 3.

The drawing and description disclose what is now considered a preferred form of the invention by way of illustration only while the broad principle of the invention will be defined by the appended claims.

What I claim is:

1. A releasable spear for pulling pipe including a mandrel having a tapered seat, a slip support, a slip carried by said support and adapted to engage the pipe to be pulled and having a seat, and means for connecting the mandrel to an operating string and through which the mandrel may be actuated into one position, relative to the slip, to bring said seats into cooperating relation whereby the slip is forced into secure engagement with the pipe, and into another position to carry the seats out of cooperating relation to permit the slip to release said pipe.

2. A releasable spear for pulling pipe including a mandrel having a tapered seat, a slip support, a slip carried by said support, and adapted to engage the pipe to be pulled
 5 and having a seat, means for connecting the mandrel to an operating string and rotatable, relative to the mandrel, in one direction to bring said seats into cooperating relation whereby the slip is forced into engagement
 10 with the pipe and in another direction to carry said seats out of cooperating relation whereby the slip is permitted to release said pipe.

3. A releasing spear including a tapering
 15 mandrel, a support associated therewith, an expansible slip on said support about the mandrel, a coupling having a threaded connection with the mandrel, means on the coupling for limiting the range of longitudinal
 20 movement of the slip relative to the coupling, and means for preventing the relative rotation of the mandrel and slip.

4. A releasing spear including a tapering mandrel, a support associated therewith, an
 25 expansible slip on said support about the mandrel, a coupling having a threaded connection with the mandrel, means on the coupling for limiting the range of longitudinal movement of the slip relative to the coupling,
 30 said mandrel, when moved into one position relative to the slip being effective to expand the slip, and said coupling being effective, when turned in one direction relative to the mandrel, to release said mandrel from the
 35 slip to permit the contraction of the slip.

5. A releasing spear including a mandrel having a tapering seat, a slip support associated with the mandrel, an expansible slip on the support about the mandrel, an actuating member having a threaded connection with the mandrel, yieldable means normally acting to hold the slip against said seat, and interlocking means between the support and actuating member whereby the slip may be
 40 unseated upon a relative rotation of said mandrel and actuating member in one direction.

6. A releasing spear including a mandrel having a tapering seat, a slip support associated with the mandrel, an expansible slip on the support about the mandrel, an actuating member having a threaded connection with the mandrel, yieldable means normally acting to hold the slip against said seat, and interlocking means between the support and actuating member whereby the slip may be
 45 unseated upon a relative rotation of said mandrel and actuating member in one direction, and means preventing the relative rotation
 50 of the mandrel and slip.

7. A releasable spear for pulling pipe including a mandrel having a tapering seat, a slip support, an expansible slip on the support about the mandrel, said slip being movable into one position onto said seat whereby

the slip may be expanded, and into another position away from said seat whereby the slip is permitted to contract, an actuating member having a threaded connection with the mandrel, means on the actuating member engageable with the support and effective to unseat said slip upon the turning movement of said actuating member in one direction.

8. A releasable spear for pulling pipe including a mandrel having a tapering seat, a slip support, an expansible slip on the support about the mandrel, said slip being movable into one position onto said seat whereby the slip may be expanded, and into another position away from said seat whereby the slip is permitted to contract, an actuating member having a threaded connection with the mandrel, means on the actuating member engageable with the support and effective to unseat said slip upon the turning movement of said actuating member in one direction, and yieldable means acting against said support and normally tending to hold the slip seated against said seat.

9. A releasable spear for pulling pipe including a mandrel having a tapering seat, a slip support, an expansible slip on the support about the mandrel, said slip being movable into one position onto said seat whereby the slip may be expanded, and into another position away from said seat whereby the slip is permitted to contract, an actuating member having a threaded connection with the mandrel, means on the actuating member engageable with the support and effective to unseat said slip upon the turning movement of said actuating member in one direction and means for preventing the relative rotation of the mandrel and slip but permitting their relative longitudinal movement.

In testimony whereof I have signed my name to this specification.
